UNITED STATES PATENT OFFICE.

HARRY V. N. SNYDER, OF CLIFTON, NEW JERSEY, ASSIGNOR TO THE MANHATTAN RUBBER MFG. COMPANY, A CORPORATION OF NEW JERSEY.

WINDING BOBBIN.

Application filed January 19, 1927. Serial No. 162,016.

My invention relates to a winding bobbin which is particularly suitable for receiving threads of rayon (artificial silk) wound thereon. The drawings show an embodiment of the invention which I now prefer, although I realize that it may be embodied in other forms.

Fig. 1 is a perspective view of the bobbin, and

Fig. 2 is a detail section greatly enlarged.

A winding bobbin which is particularly suitable for receiving threads of delicate rayon, and which shall embody the desirable features and avoid those things which have been found in practice to be objectionable, has been difficult to obtain. Rayon is made from a cellular structure, usually wood, which has been dissolved and suitably treated. In its liquid and somewhat viscous condition, it is squirted through extremely minute holes in a head, usually of platinum, into a bath which immediately causes the fluid to set, forming a minute filament like a single filament of natural silk. A number of such filaments as they come from the fixing bath are collected into a thread and then wound upon a bobbin. The filaments are extremely delicate, and any undue tension or sudden jar is likely to break them, either before becoming completely set in the bath or when on the bobbin. As the threads are wound on the bobbin, its diameter naturally increases and if this exerts too much tension, the filaments, or some of them, will be broken. They carry some acids or alkalis, or both, and the bobbin must be unaffected by them. A metal bobbin although desirable from a mechanical standpoint, is undesirable from a practical standpoint due to the acids and alkalis which not only affect the bobbin itself but the metal from the effects of the acid solution will react upon the rayon threads and discolor or otherwise injure them. Many bobbins have been used, such as various special metals, rubber, bakelite, metal with a coating of baked enamel and others. All of these have many very good characteristics, but do not give entirely satisfactory service because they lack one or more necessary characteristics to work satisfactorily through the entire process. Wooden bobbins, such as used for winding cotton or natural silk, have been tried but are not suitable. It is desirable that the air be allowed to penetrate freely through the bob-

bin to the interior of the mass of rayon wound thereon. It therefore should be hollow and full of perforations. It should be as light as possible and therefore thin. Thin metal is thus suggested, but this has extremely undesirable characteristics. Sheet iron, for example, is attacked by the acids and alkalis present, and the attacked portions react upon the rayon threads and discolor or otherwise injure them. It is a somewhat difficult and expensive job to form perforations through metal which shall be free from burrs and roughnesses which are likely to injure the filaments.

The rayon filaments contract somewhat after they are set in final form and, while the individual filament is weak, collectively this contraction exerts a considerable tension longitudinally of the thread. The bobbin should therefore be so made that it will resist the distortion. Bobbins that have the mechanical strength do not have acid and alkali resistance and vice versa. A hard rubber bobbin made entirely of rubber will resist the acid and alkali but due to the nature of the material when vulcanized rock hard is brittle and will chip and crack, and it will also soften up when run through the heated alkali and acid solutions, which renders it unsatisfactory as the tension of the rayon threads during the drying process distorts the bobbin out of shape, causing winding difficulties, difficulty in removing the bobbin and other disadvantages.

A metal bobbin covered with baked enamel was tried, but this is objectionable for some of the above reasons. It is not easy to make, especially with a thin body, where even the walls of the perforations have to be protected, and when it cracks or chips as it does it is open to the same objection as an all-metal bobbin.

A successful bobbin suitable particularly for winding rayon therefore embodies features which are diverse and have been thought to be impossible of practical accomplishment in a unitary structure. By my invention I have, however, been able to overcome the above objections, while at the same time retaining the desired features of advantage.

I have shown in the drawings a cylindrical bobbin A which has a body B of thin metal such as sheet iron or aluminum and which is therefore capable substantially of resist-

2

ing the distortion due to the contraction of the threads and the winding tension but can yield slightly and is elastic enough to spring back to form. It is formed with a 5 multitude of perforations C which communicate with its hollow interior. The exterior and interior surfaces are entirely covered with a thin layer of rubber which is resistant to acids and alkalis. This rubber is 10 preferably applied by placing around and in contact with its exterior surface, and also with its interior surface, a thin layer of unvulcanized rubber, e. g. $\frac{1}{32}$ nd of an inch. It may then be put into a vulcanizer which 15 exerts pressure both radially inward against the outer layer and radially outward against the inner layer of rubber. This may be done by one of the well known vulcanizers. It is not necessary to describe this more particularly, as rubber manufacturers are familiar 20 with such process.

The pressure exerted forces the rubber layers into intimate contact with the exterior and interior surfaces of the metal body at 25 every point and holds it there while being vulcanized. It also forces the rubber into the holes but leaves a thin diaphragm across each hole. This diaphragm may then be removed by a suitable punch or drill, small 30 enough not to touch the walls of the holes, that is, so as to leave a film of rubber completely enclosing and covering the wall of the hole in the metal body.

A fragment is illustrated (greatly enlarged) in Fig. 2. In this the metal body 35 B, with the hole therein as shown, is illustrated as covered with the thin rubber layers D, D'. It will be observed that the wall E of the hole is also completely covered and protected by the rubber. The diaphragm of rubber is formed at F, which is, as shown, removed by the punch or drill above mentioned.

As shown in Fig. 1, the holes are preferably arranged in patterns, such as a row 45 or a combination of rows, which repeat themselves regularly all around its periphery. This allows of the use of a "gang" punch or drill for removing the rubber diaphragms originally closing the holes.

The completed bobbin has all of the desirable characteristics above specified and none of the objectionable features. As a 55 whole, it is resistant to compression tension. At the same time there are no metal parts exposed to the action of the acids and alkalis, even the walls of the holes. The filaments therefore cannot be injured from this cause.

Also as the bobbin has a multitude of perforations throughout its body portion, any thread

will therefore pass across a large number of perforations in being laid around the periphery. Air may circulate through the bobbin and into the mass of rayon thereon.

The vulcanization should be carried beyond the point where the rubber is soft like that of a pencil eraser, and yet stop short of so called rock-hardness which would render it brittle. When this is done with a thin rubber layer, for example one thirty-second 65 of an inch in thickness, a surprising result is attained. When the bobbin is smoothed or polished by friction in the ordinary manner, or even after it attains this relatively polished surface by use, the body of the rubber 70 film underneath the exterior skin will be found to be somewhat yielding so that it can be indented by pressure of a sharp instrument like a pin, but yet is extremely tough and resistant so that it is practically impossible to crack or chip it in the hard usage 75 to which such bobbins are subjected, even by sudden shocks such as when the bobbins are dropped onto a hard floor or thrown together in a receiving box. At the same time 80 the outer surface has the appearance of a rock-hard structure and yet has such a high molecular cohesion that it is practically impossible to chip or crack it. Whether these 85 results are due to the fact that the bobbin 90 has a thin metal body overlaid with thin films, or to the heat generated by the friction or to air oxidation, or to a combination of 95 these and other causes, I have not determined. However, the result is a bobbin 100 completely covered with rubber and which is as a whole resilient to ordinary distortion and shocks, and yet is so extraordinarily tough 105 that it will not crack or chip, which has long been sought in this art.

What I claim is:

A winding bobbin suitable for having threads of rayon wound thereon, comprising a hollow, thin, slightly resilient but substantially distortion-resisting body having a 105 multitude of perforations through its surface and communicating with its hollow interior, the exterior and the interior of the winding surface of the bobbin being entirely covered with a thin layer of rubber resistant to acids and alkalis and vulcanized to such a degree between softness and rock-hardness as renders the covering material somewhat yielding but tough and substantially resistant to cracking or chipping and with an 110 exterior surface of high molecular cohesion.

Signed at New York, N. Y., this 18th day 115 of January 1927.

HARRY V. N. SNYDER.
